UNITED STATES PATENT OFFICE.

HENRY F. RUSSELL, OF SYRACUSE, NEW YORK.

SKYLIGHT-OPERATOR.

No. 844,691.

Specification of Letters Patent.

Patented Feb. 19, 1907.

Application filed March 5, 1906, Serial No. 304,192.

To all whom it may concern:

Be it known that I, HENRY F. RUSSELL, a citizen of the United States, and a resident of Syracuse, in the county of Onondaga, in the State of New York, have invented new and useful Improvements in Skylight-Operators, of which the following, taken in connection with the accompanying drawings, is a full, clear, and exact description.

This invention relates to the class of skylights or scuttles which are hinged to the frame surrounding the opening; and the invention consists in improved means for expeditiously and conveniently opening and closing the skylight or scuttle, as hereinafter described and claimed.

In the accompanying drawings, Figures 1 and 2 are vertical longitudinal sections of a skylight embodying my improvements shown in open and closed positions. Fig. 3 is a horizontal transverse section on the line 3-3 in Fig. 1. Fig. 4 is an enlarged transverse section of the push-bar, taken on the line 4-4 in Fig. 1. Figs. 5 and 6 are enlarged front and side views, respectively, of the means for locking and unlocking the skylight. Fig. 7 is a side view of a modification of said locking and unlocking means, and Fig. 8 is a transverse section on the line 8-8 in Fig. 7.

Similar letters of reference indicate corresponding parts.

a represents the frame which surrounds the opening to which the skylight is applied.

b denotes the skylight or scuttle, which may be of any suitable construction and shape to properly fit to the frame *a*, to which it is connected by means of suitable hinges *c c*.

D represents a push-bar for raising the skylight to its open position. I prefer to make this push-bar adjustable in length to adapt it for skylights of different sizes. This adjustability I prefer to obtain by constructing the said push-bar of telescopically-jointed members *d d'*.

The upper end of the member *d* is hinged at *e* to a bracket *f*, attached to the skylight or scuttle at a short distance from the free edge thereof. Said member consists of a metal tube which is split longitudinally, as shown at *g* in Fig. 4, to render it compressible and capable of tightly embracing the upper end portion of the lower member *d'*, which is inserted therein. A split collar or band *h* embraces the split portion of the upper member *d* and is formed with perforated ears *h' h'*, receiving through them a bolt *i*, provided with

a nut *i'*, by means of which the collar *h* can be tightened to cause the member *d* to firmly clamp the member *d'* therein. By loosening the said collar the lower member is permitted to be pushed a greater or less distance into the upper member, and thus adjust the length of the push-bar *D* as may be desired.

j j are braces which are hinged at one end to brackets *k k*, attached to the skylight or scuttle *b* near the hinged edge thereof and at short distances from the side edges. Said braces converge from their said hinged ends and have the opposite ends perforated and fitted to the outer sides of the ears *h' h'* of the split collar *h* and receiving through them the bolt *i*, which thus serves the additional function of pivotally connecting said braces to the push-bar *D*. Said pivotal connection allows the collar *h* to be adjusted lengthwise of the push-bar to obtain proper coaction of the braces with the push-bar.

l represents a latch for locking the skylight or scuttle *b* in its closed position. Said latch is hinged at its lower end, as shown at *l'*, to a plate *n*, which is fastened to the inner side of the frame *a* by screws *n' n'*, as more clearly shown in Fig. 5. The upper end of the latch *l* is formed with a right-angled extension or hook *l''* to engage a staple *o*, which is rigidly secured to the under side of the skylight or scuttle. The said latch is automatically locked by means of a suitable spring, which may be either of the form of a plate *p*, which is attached at its upper end to the latch near the upper or free end thereof, as more clearly shown at *p'* in Fig. 6. The lower end *p''* of said spring bears on the plate *n*, on which it is adapted to slide. The spring is curved or otherwise shaped to cause it to force the upper end of the latch toward the frame *a*, as shown in Fig. 2, and into a position to engage the staple *o* of the skylight when in its closed position. The upper end of the plate *n* has rigidly projecting from it a staple *t*, which receives through it the upper portion of the latch *l* and serves as a guide and a stop for the latch. Another form of spring designed to perform the aforesaid function is shown in Figs. 7 and 8 of the drawings and consists of a spirally-bent wire *r*, surrounding a bolt *r'*, the ends of which pass through perforated lugs *s*, projecting from the plate *n*, and through perforated ears *r''* on a wide portion of the latch *l*, which is thus hinged to the plate *n*. Both ends of the spring *r* extend downward from the bolt *r'*.

110

and one of said ends bears on the plate n , and the opposite end bears on a downward extension t' of the latch l at the side facing the said plate. In this case the plate n is provided with a suitable stop t^2 , which comes in contact with the latch extension t' when the latch is thrown into its unlocked position. In this construction the staple t , hereinbefore mentioned, is dispensed with by the use 10 of the stop t^2 and by the hinging of the latch to the ends of the bolt r' , which guides the latch and sustains it laterally. To the back of the lower portion of the latch is attached a bracket u , to which is pivoted a pulley u' . 15 Upon this pulley rides a rope v , one end of which is attached to the lower end of the push-bar member d' , and the opposite end is free for manipulation. The skylight drops by gravity to its closed position and is locked 20 by the latch l being allowed to engage the staple o by relieving the pulley u' from the draft of the rope v .

To open the skylight, a person draws down the free end of the rope v . The strain exerted on this rope presses on the upper part 25 of the pulley u' , and thereby tilts the latch so as to loosen its hold on the staple o . A further draft on the said rope draws the lower end of the push-bar D toward the pulley u' , and thus causes said push-bar to rise and push the skylight to its open position, as shown in Fig. 1 of the drawings, in which position it can be retained by tying the lower end of the rope to a suitable stationary object. I prefer, however, to tie the rope to the bracket u by providing the pulley with a branch groove u^2 , leading to one end of the pulley, as shown in Fig. 8. By allowing the rope v to enter the groove u^2 while gradually 35 releasing the free end of the rope from strain the rope becomes jammed and bound on the inner side of the bracket u .

What I claim is—

1. The combination, with a hinged skylight and its supporting-frame, of a push-bar pivotally connected to the skylight, a collar adjustably attached to the lower portion of the push-bar, braces pivotally connected to the skylight near the side edges thereof and pivoted to the aforesaid collar, a pulley supported on the aforesaid frame under the free edge of the skylight, and an operating-rope traversing said pulley and connected to the lower end of the push-bar as set forth. 45
2. The combination, with a hinged skylight, of a push-bar composed of a tubular upper member pivotally connected at one end to the skylight and split longitudinally at its opposite end and a lower member inserted in the split end of the upper member, a split collar embracing the split portion of the upper member and provided with means for 55

tightening it on said member, levers pivotally connected to said collar and to the skylight near the hinged edge thereof, and means for 65 operating said push-bar.

3. The combination, with a hinged skylight, of a push-bar connected to the under side of the skylight and adjustable in length, braces connecting the lower portion of said 70 push-bar to the side portions of the skylight, and means for operating said push-bar.

4. The combination, with a hinged skylight, of a push-bar connected to said skylight and composed of telescopically-jointed 75 members adjustably clamped together, braces connecting the lower portion of said push-bar to the side portions of the skylight, and means for operating the push-bar.

5. The combination, with a hinged skylight and its supporting-frame, of a push-bar connected to the skylight, braces connecting the lower portion of the push-bar to the side portions of the skylight, a latch connected to the supporting-frame and adapted to lock 80 the skylight in its closed position, a pulley connected to said latch, and a rope traversing the pulley and connected at one end to the lower end of the push-bar as set forth.

6. The combination with a hinged skylight and its supporting-frame, of a push-bar pivotally connected to the skylight, braces connecting the lower portion of the push-bar to the side portions of the skylight, a latch hinged to the supporting-frame and adapted 95 to lock the skylight in its closed position, a spring forcing the latch to its locked position, a pulley connected to the back of the latch, and a rope traversing said pulley and connected at one end to the lower end of the push-bar as set forth. 100

7. The combination, with a hinged skylight and its supporting-frame, of a push-bar connected to the under side of the skylight and adjustable in length, braces connecting the lower portion of the push-bar to the side portions of the skylight, a plate attached to the supporting-frame under the free edge of the skylight, a staple projecting from the upper end of said plate, a latch hinged to the 110 lower end of the plate and passing with its upper end through the staple and terminating in a locking-hook, a staple attached to the skylight and engaging the said hook, a spring forcing the latch to its locking position, a 115 bracket projecting from the back of the latch, a pulley pivoted to said bracket, and a rope traversing the pulley and connected at one end to the lower end of the push-bar substantially as set forth.
